UNITED STATES PATENT OFFICE.

EDWIN N. DODGE, OF CLAREMONT, MINNESOTA.

CUFF-HOLDER.

SPECIFICATION forming part of Letters Patent No. 391,739, dated October 23, 1888.

Application filed June 29, 1888. Serial No. 278,540. (No model.)

To all whom it may concern:

Be it known that I, EDWIN N. DODGE, a citizen of the United States, residing at Claremont, in the county of Dodge and State of Minnesota, have invented certain new and useful Improvements in Cuff-Holders, of which the following is a specification, reference being had therein to the accompanying drawings, in which—

10 Figure 1 represents a perspective view of my device applied to a cuff and shirt-sleeve; Fig. 2, a detached perspective view of the holder and adjuster; Fig. 3, a detail sectional view taken through the adjustable button.

15 This invention has relation to certain new and useful improvements upon that class of devices employed to adjustably and removably attach men's cuffs to the stay-bands of shirt-sleeves, whereby the cuffs may be adjusted to 20 any position with respect to the coat-sleeves the wearer may desire and be securely held in such adjusted position, as will be more fully hereinafter specified.

This invention has for its objects to provide 25 a simple and inexpensive yet practical device of this character; and it consists in certain novel features of construction, which will fully herein appear and be particularly pointed out in the claims appended.

30 Referring to the drawings by letters, A designates a metallic bar provided at its ends with means for detachably attaching it to a stay-band of a shirt-sleeve, in this instance small clips *a a* and set-screws *a' a'* being employed for this purpose, these set-screws being tapped into the upper arms of the clips and adapted to clamp the stay-band between their 35 ends and the lower arms of the clips, as clearly shown in the drawings. I prefer this method 40 of attaching the bar A to the shirt-sleeve; but it is evident that I may employ other devices without departing from my invention.

Embracing the bar A and adapted to slide 45 freely back and forth upon it is a loop, *b*, which has formed integral with it, upon its upper side, a tubular extension or shank, *b'*, this shank being preferably formed with an annular flange, *b''*, around its upper edge, which serves to prevent the cuff from loosening the

button. Tapped into the shank *b'* and loop *b* 50 is the threaded stem of a button, *c*. This stem passes entirely through the said shank and loop and bears against the upper face of the bar A, serving to hold the said loop at any desired position on the bar. To apply the device 55 the bar A is first attached to the stay-band of the sleeve, as shown in Fig. 1. The shank *b'* is then passed through the button-holes of the cuff and the button screwed into the shank until it bears against the bar A. By loosening 60 the button a little the cuff may be adjusted to any position upon the bar A, and then secured in such adjusted position by tightening up the screw again.

It will be observed that an essential feature 65 of this device is the button *c*, which serves the double purpose of holding the cuff upon the shank *b'* and securely holding the cuff in any of its adjusted positions. The device is extremely simple and may be made at a minimum cost—two great desiderata with devices 70 of this character.

Having thus fully described my invention, what I claim as new, and desire to secure by Letters Patent, is—

1. The combination, with a bar provided 75 with clips *a a* at its ends and set-screws *a' a'* tapped into the upper arm of these clips, of an adjustable button adapted to slide upon the said bar, substantially as herein set forth. 80

2. The combination, with a bar provided with clips having set-screws for attaching it to a shirt-sleeve, of a loop loosely embracing the said bar, this loop being provided with a hollow vertical shank, this shank having formed 85 integral with it at its outer end an annular flange, *b''*, and a button provided with a screw-threaded stem, the said stem being tapped into the said shank and adapted to bear upon the upper surface of the said bar, substantially as 90 herein set forth.

In testimony whereof I affix my signature in presence of two witnesses.

EDWIN N. DODGE.
